INVALID'S CHAIR

George A. Sill and Herbert L. Thompson,
Elgin, Ill.

Application July 31, 1940, Serial No. 348,906

5 Claims. (Cl. 155—30)

Our invention relates to improvements in apparatus or equipment for use by invalids.

Our invention relates more particularly to improvements in self-propelled invalids' chairs or similar devices.

It is a well known fact that people who are bed-ridden, crippled, or invalids to the extent that they are more or less helpless, are generally spiritless in heart and do not have a state of mind conducive to cheerfulness or hope because of the realization that they are such a burden upon other people. Their every slight need requires the attention of others and constantly reminds them of their own helplessness. If mechanical devices could be devised which could be used by such people so that they could wait upon themselves at least to a degree, it would have a heartening effect upon them and naturally relieve others of a portion of the burden of attending them.

Therefore, the principal object of our invention is to provide an improved invalid's or crippled person's wheeled chair.

A further object of the invention is to provide a chair of this type which is capable of being easily handled by an invalid for moving from place to place and yet which, when desired, will automatically be firmly located wherever the invalid desires to have the chair disposed in a stationary location.

A further object of the invention is to provide adjustable arm supports to suit individual requirements as to height, but capable when desired, of being easily swung down so that an invalid can slide sideways from the chair into a bed or vice versa.

A further object of the invention is to provide a highly improved invalid's chair having various other features such as an adjustable back, an adjustable seat and arm rests, and easily operated mechanism for making these adjustments.

Other objects and advantages will be more apparent from the following description wherein reference is had to the accompanying two sheets of drawings, upon which

Fig. 1 is a front perspective view of my improved invalid's chair;

Fig. 2 is a vertical sectional view taken generally on the lines 2—2 of Fig. 1 and showing the foot rest raised when the chair assumes the dotted position shown;

Fig. 3 is a plan sectional view taken generally on the lines 3—3 of Fig. 2;

Fig. 4 is a fragmentary side elevational view showing one of the arm rests dropped down in

dotted-line position to permit movement of the patient from the chair sideways to a bed;

Fig. 5 is an enlarged sectional view of the arm rest mechanism taken generally on the line 5—5 of Fig. 4; and

Fig. 6 is an enlarged fragmentary view thereof taken generally on the lines 6—6 of Fig. 5.

In the embodiment of the invention which has been illustrated, we have shown generally an invalid's or crippled person's chair which may comprise the seat 10, the back 12, a pair of arm rests 14 and 16, a foot rest 18, and a wheeled carriage 20 upon which all of these various parts are supported.

15 The seat, back and arm rests may constitute an assembly which is supported by a vertical post 22 that is mounted in a bracket 24 secured to the axle 25 of the wheeled carriage. The post 22 may engage a bracket 26 secured to the lower side of the seat 10.

15 The axle 25 may support at opposite ends a pair of rubber tired wheels 28 which are of sufficient diameter so that a person sitting in the chair can easily grasp the same to secure forward movement of the chair. We provide an arm 30 extending rearwardly from the bracket 24 formed with a downwardly turned portion engaging in a small wheel supporting bracket 32. The rubber tired wheel 34 may be mounted therein in such a position that it may revolve about the axis of the bracket. We provide a resilient connection 36 between the arm 30 and the bracket so that when a person on the seat sits back, the weight is sufficient to press the spring 36 and lower the arm 30 about an inch. The purpose of this movement is to raise the foot rest 18 which is carried by a pair of brackets 38 that are rigidly connected to the axle 25.

25 From the above it is clear that when a person sits back in the chair, compressing the spring 36, the foot rest 18 will be raised from the floor and the chair may be propelled about. Whenever a person sits upright, the foot rest will be fixedly positioned upon the floor and thus prevent any movement of the chair during this time.

30 We have provided means for tilting the back of the chair. The side supports 40 may be pivotally mounted upon a cross rod 42 fastened in the extended ends 10a of the seat. We provide a bracket 44 connected by suitable bolts 46 to the lowermost ends of the side supports 40. We mount a handle 48 through a screw-threaded opening 50 in the bracket 44 and rotatably connect the same in a boss 52 that is pivotally connected in the bracket 26. With this connection

35 40 45 50 55

the back may be tilted to a desired angle by simply turning the handle 48 and moving the lowermost part of the back to and fro.

We have also provided adjustment means for the arm rests 14 and 16. This means may include a vertical standard 54 for each of the arms 14 and 16. The standard 54 is provided with an elongated slot 56 through which a bolt 58 is extended. The bolt 58 is fastened in the sides of the chair seat 10 and may extend through an opening in a clamp member 60 provided for each arm. The clamp member 60 may carry at one end a friction member 62 which includes a hand wheel, a pad 64 and a screw-threaded shank mounted in the upper end of the clamp 60. Thus by loosening the friction pad, the arm rest may be raised or lowered by sliding it up and down on the bolt 58, and when a desired height is reached the clamping means may be fastened, thus securely fixing the arm in the desired position.

In order that the arms of the chair may be swung out of the way so that a patient can move himself sideways from a bed on to the chair, or from the chair to a bed or water closet or other position, we have provided the extension 54a at the lower end of the standard 54. Thus when the clamping means 60 is loosened, the arm 14 may be raised till the bolt 58 is in the lower end of the elongated slot and the arm may be rotated approximately ninety degrees with the portion 54a resting against a shoulder 66 formed upon the bracket 68 that is fastened at the side of the chair 10. The arm is thus held in a fixed position out of the way of the person using the chair, and as soon as he has transferred from a bed to the chair, he can raise the arm, fasten it in a desired position, and have arm rests during the time he is occupying the chair.

While we have illustrated and described a specific embodiment of the invention, it will be apparent to those skilled in the art that changes and modifications may be made in the exact details shown, and we do not wish to limit our invention; rather what we desire to secure and protect by Letters Patent of the United States is:

1. An invalid's chair comprising a seat, back and arm rests, a three-wheeled carriage to support the same, said carriage having a pair of large wheels on opposite sides of said chair, an axle therebetween, a bracket on said axle, an arm extending rearwardly therefrom, a small wheel positioned in a second bracket at the end of said arm, and a resilient connection between said second bracket and said arm permitting back and forth tilting of the chair on the carriage, a flat foot rest normally resting on the floor supported from said axle and so arranged that tilting movement of the chair raises the same so the chair may be moved about by the occupant.

2. An invalid's chair comprising a seat, back and arm rests, a three-wheeled carriage to sup-

port the same, said carriage having a pair of large wheels on opposite sides of said chair, an axle therebetween, a bracket on said axle, an arm extending rearwardly therefrom, a small wheel positioned in a second bracket at the end of said arm, and a resilient connection between said second bracket and said arm permitting back and forth tilting of the chair on the carriage, a pair of forward and downwardly disposed brackets secured to said axle, a flat foot rest normally resting on the floor supported by said brackets from said axle and so arranged that tilting movement of the chair raises the same so the chair may be moved about by the occupant.

3. The combination with an invalid's chair having a seat, back, arm rests and means associated with said arm rests for moving the same to an inoperative position, of a three-wheeled carriage to support said chair, said carriage having a pair of large wheels on opposite sides of said chair, an axle therebetween, a bracket on said axle, an arm extending rearwardly therefrom, a small wheel positioned in a second bracket at the end of said arm, and a resilient connection between said second bracket and said arm permitting back and forth tilting of the chair on the carriage, a flat foot rest normally resting on the floor when the chair is in a stationary position, said foot rest supported from said axle and so arranged that tilting movement of the chair raises the same so the chair may be moved about by the occupant.

4. A chair of the type described comprising a seat, back and arm rests, a wheeled carriage to support the same, said carriage including a framework having a main axle, a pair of wheels journaled on said axle and positioned upon opposite sides of said chair, a horizontally disposed foot rest connected to the front of said framework and normally positioned resting on the floor, and a wheel member connected to the back of said framework and normally in contact with the floor, and spring means mounting said wheel member on said framework whereby the framework may be tilted rearwardly against the tension of said spring means so that the foot rest may be raised from the floor to permit moving about of said apparatus upon its wheels.

5. Apparatus of the class described comprising a tiltably mounted carriage, a chair rigidly mounted on said carriage, said carriage having spaced front wheels and a resiliently mounted back wheel at all times in contact with the floor, a foot rest rigidly connected to said carriage and normally held in contact with the floor through the tension of said resiliently mounted back wheel, said resiliently mounted back wheel being compressed when the weight is shifted in said chair to raise said foot rest from the floor.
